UNITED STATES PATENT OFFICE

CHARLES E. BENNETT, OF DECATUR, GEORGIA

SUSPENDED EXCESS POTENTIAL DRAIN

Application filed June 19, 1928. Serial No. 286,650.

This invention relates to devices for the protection of high tension power transmission lines and of power stations in such lines.

It is customary in such lines to insulate the line conductors from their supports, the insulators being designed to prevent flashing over, with consequent loss of power, under normal conditions or even under certain abnormal conditions where the normal potential of the line is not greatly exceeded. Such are ordinary conditions. It is not practicable however to insulate the line conductors to such an extent that excess of potential, or superpotential as it is called, due generally 15 to lightning discharge could not be drained away to ground.

Superpotential drains are therefore provided at various points along the transmission line to relieve the line of this excess potential caused by lightning discharge. If the substations or power stations are less capable of withstanding an excess potential on their equipment than the lines leading thereto, the protecting drains are placed near 20 the stations on the conductors feeding thereto or receiving power therefrom. If the line conductors and the line equipment are less capable of withstanding superpotential, the drains are located along the line in such 25 number as conditions require.

In general, an excess potential drain consists of an arcing gap and an interrupter. A common practice heretofore has been to support the terminals of the gap on the pole or 30 tower structure which carries the line conductor. The interrupter in such arrangements has been separately supported on the tower and connected between one terminal of the arc gap and ground, the other terminal 35 of the gap being connected to the conductor.

The interrupter is a device which normally establishes a connection to ground but which will break that connection after relief 40 of excess potential therethrough. Otherwise, once an arc was established across the gap and the excess potential was relieved, the line conductor would remain grounded. In some interrupters there is provision for reestablishing the conductive connection between the

one pole of the gap and ground. As the word "interrupter" is used here, it includes both types. By "ground" of course, is meant any object at substantially earth potential.

The preferred interrupter is of the electrolytic type in which the excess potential is relieved by discharge to ground through a volatile electrolyte, after which the electrolyte re-establishes the connection to the arc gap. Such an interrupter is shown here and conforms to that of my application for patent, Serial Number 137,310 filed September 23, 1926. I prefer that type, because, in it, the interruption of the arc occurs within one or two cycles and because, as a structure, it has desirable characteristics of flexibility, 55 strength and ease of manufacture, installation and replacement.

According to the present invention, in its preferred form, I propose to suspend the superpotential drain device between the line conductor and the earth or the lower end of the tower or pole which carries the line conductor. The conductor is suspended by a string of insulators and the drain device is attached at its upper end to the conductor itself or preferably to the lower end of the insulator string and in line therewith. In either case, the drain device is suspended 60 from the string of insulators which support 65 the line conductor and insulate it from ground.

The drain device may be arranged with the means forming the arc gap on the line side of the interrupter or on the ground side. When on the line side, the gap is best formed by an insulating body which may consist of a string of units, as in the case of the line insulation mentioned above, and which has poles or arcing terminals at its ends. The interrupter is then suspended from the lower 70 end of this insulating body.

Whether the arc gap is on the line side or on the ground side of the interrupter, its insulating strength is less than that of the line insulation so that the discharge of excess potential in the line will be by way of the drain device rather than over the line insulation. It is understood that the description of the drain device as being suspended from the 75 80 85 90 95 100

line supporting and insulating means does not require, although it includes, a free suspension since it generally is desirable to give the lower end of the drain device lateral support at least. With the type of interrupter which I prefer to use, it is best to support the lower tank from the earth or from the lower end of the line carrying tower in order to prevent stain on the tubes.

10 It is an object of the invention therefore to protect transmission line and power house equipment by providing at the points needing protection a connection to ground including an interrupter and an insulating medium 15 of less strength than the regular line insulation between the conductors and their supports.

It is a further object to provide a way of suspending the drain device so that it will be 20 easily installed, will not be hazardous and will be efficient in its operation.

The present preferred construction is described hereinafter and is illustrated in the accompanying drawings.

25 In the drawings:—

Figure 1 is an elevation view of a transmission line support showing interrupters installed according to this invention;

30 Figure 2 is a profile view of the same, and Figure 3 is a more detailed view of the suspension type of connection between the drain and the line;

35 Figures 4 and 5 are views of modifications in which the arc gap is on the ground side of the interrupter.

The construction is shown in a three-wire transmission line, with a similar arrangement for each wire, as in Fig. 1. The conductors A are suspended from a cross arm 2 supported on poles 3 or other usual line carrying structures. Braces 4 give rigidity and strength to the supporting structure. The suspension of the conductors is by insulators B of any suitable type connected to the cross bars at points spaced from the vertical supports 3 in the known manner to insulate the conductors from the supports in all directions. Below each conductor is a super-potential drain consisting of an insulating body C forming an arc gap and an interrupter D of the type shown in my co-pending application referred to above. This body C is of less insulating strength than the insulation B between the line conductor and the cross support 2. The terminals 8, 9 at the ends of the insulator C may be of the horn or ring type or of any suitable construction to permit an arc to bridge the insulating body C without following the surface of the insulators.

40 Referring to Fig. 3 in which there is a more detailed view, it will be seen that the line insulation B (shown broken) is of the Hewlett type and, for instance, may consist of seven units connected to the arm 2 by a bolt 5.

The conductor A is secured to the insulators by the attaching member 7 and is supported thereby from the cross-arm. The insulating body C is of the same type as B but has fewer units so that its insulating strength is less than that of B, three units being shown in Fig. 3 as a possible number to use where seven are used in the line insulation B. This body C is suspended directly below the insulation B by a conducting link 6 which forms part of the attaching member 7. At the lower end of this link is an arcing ring 8 surrounding the insulators B and at the lower end of the insulators is another ring 9 facing ring 8, the two providing an arcing gap. As shown, the ring supports are integral with the links 6 and 11. Without the rings or their equivalents, arcing might take place from link 6 to link 11 and would injure the insulating units therebetween.

45 To link 11 is conductively attached the upper tank 12 of a superpotential drain or interrupter of the electrolytic type. The tank 12 has a gauge 13, vent 14 and a plug 15 which may be removed for the introduction of electrolyte into the tank, all as shown in my copending application Serial No. 137,310. The insulating tubes 16 are connected to the lower end of the tank 12 and extend into the lower tank 17 which is connected to ground at 18. The body of electrolyte is contained in both tanks but does not fill either, the bodies of air above the liquid in the tanks serving as a cushion. The tubes 16 are of low grade rubber composition so as to be flexible and yieldable but of strength to resist the force of the arc and of the volatilization of the liquid. The tubes are longer than the normal arc-over spacing for which they are to be used and, by reason of this, the arc is drawn out and broken within the tubes. This and the yieldable characteristic of the tubes give the speedy operation which makes this type of interrupter preferable. It is, however, within the scope of this invention 50 to use other types of interrupter.

55 I wish particularly to call attention to the fact that the arcing rings at the ends of the insulator C have no connection to ground except through the interrupter. In previous practice the arcing terminals have been supported on grounded insulating standards which may flash over ahead of the operation of the interrupter and thus cause a serious line short circuit to ground with no provision for its interruption after the excess potential is relieved. By the present arrangement in which the means forming the arcing gap are suspended from the means by which the conductors are suspended, either by direct connection to this line suspension means or to the conductor itself, and are in contact solely with the conductor and the interrupter, this hazard is avoided.

60 The operation is as follows. Assuming an

excess of potential in conductor A due to a lightning discharge, there will be a difference of potential between rings 8 and 9 since the latter is grounded through the interrupter.

5 By reason of the greater number of units in insulator B than in C, the difference of potential necessary to cause flash-over at B is greater than at C and the flash-over will occur therefore at C.

10 The arcing rings prevent the arc from following the insulators themselves and if the arc does not play for too long a time, the insulator C will be uninjured. As soon as an arc is established across the rings and

15 the excess is relieved through the electrolyte to ground, the drain connection is broken by volatilization of the electrolyte in tubes 16 due to the heat generated by the discharge, this occurring in one or two cycles in an inter-

20 rupter of the type shown. The arc across 8, 9 will of course be then broken but upon re-establishment of the electrolytic path through the tubes 16, the apparatus will be in position to relieve further excess potential in the line

25 if there is any. The interrupter shown is peculiarly useful in that it interrupts the ground connection in one or two cycles and thus prevents a long continued play of the arc between rings 8 and 9 which might injure

30 the insulators C.

If, by chance, the tubes 16 become defective and a discharge occurs, the tubes will burst and let the electrolyte out breaking the connection and preventing reestablishment of it.

35 The unit is then not a hazard on the line.

The particular way shown in which the excess potential drain is installed in the transmission system has many advantages. It may be added to an existing line with no diffi-

40 culty. The arc gap terminals are in contact solely with parts which are either well insulated from ground or grounded through the connection designed for the relief of excess potential thus avoiding the hazard of short

45 circuits to ground by way of parts not designed for that purpose.

In Figures 4 and 5 are shown modifications in which the means forming the arc gap C are placed on the ground side of the interrupter D. The interrupter D is suspended in the same manner as the insulating body C in Figures 1, 2 and 3 and, therefore, in these figures, the connection is shown diagrammatically with the line insulation omitted.

55 The insulating body C may be suspended from the lower end of the interrupter and connected to ground by a wire, but where an interrupter of the sort shown here is used, it is preferable to support the insulating body separately, as by the cross member 20 which would be near the lower end of the tower, to avoid undue tension on the tubes connecting the tanks of the interrupter.

65 Various modifications of the structures

shown are possible all within the scope of the following claims.

I claim—

1. In a transmission line, a line conductor, insulating and supporting means for the line conductor, supporting and insulating it from ground, means forming an excess potential drain suspended from said supporting and insulating means, said drain comprising an interrupter and an insulating body 70 with arcing terminals at its ends.

2. In a transmission line, a line conductor, means supporting the line conductor and insulating it from ground, means forming an excess potential drain suspended from the line conductor supporting and insulating means, said drain comprising an interrupter 80 and an insulating body with arcing terminals at its ends, the body being of less insulating strength than the line insulation. 85

3. In a transmission line, a line conductor, means supporting said conductor and insulating it from ground, means forming an excess potential drain for said conductor, said means comprising an insulating body 90 suspended from said first named means, said body having an insulating strength less than said line conductor insulating means, and a conductive connection from said insulating body to ground. 95

4. In a transmission line, a line conductor, means supporting said conductor and insulating it from ground, means forming an excess potential drain for said conductor, said means comprising an insulating body suspended from said first named means, said body having an insulating strength less than said line conductor insulating means, and means connected to said body normally establishing a connection to ground, said last mentioned means being adapted to interrupt the ground connection upon discharge there-through. 100

5. In a transmission line, a line conductor, means supporting said conductor and insulating it from ground, means forming an excess potential drain for said conductor, said means comprising an insulating body suspended from said first named means, said body having an insulating strength less than said line conductor insulating means, and means connected to said body normally establishing a connection to ground, said last mentioned means being adapted to interrupt the ground connection upon discharge there-through and to reestablish the connection thereafter. 115

6. In a transmission line, a line conductor, means supporting said conductor and insulating it from ground, means forming an excess potential drain for said conductor, said means comprising an insulating body suspended from said first named means, said body having an insulating strength less than said line conductor insulating means, an arc- 120

125

130

ing pole at each end of said body, one pole being in conductive connection with the line conductor, and a conductive connection from the other pole to ground.

7. In a transmission line, a line conductor, means supporting said conductor and insulating it from ground, means forming an excess potential drain for said conductor, said means comprising an insulating body suspended from said first named means, said body having an insulating strength less than said line conductor insulating means, an arcing pole at each end of said body, one pole conductively connected with the line conductor and means normally establishing a ground connection from said other pole, said last mentioned means being adapted to interrupt said connection upon discharge therethrough.
8. In a transmission line, a line conductor, means supporting said conductor and insulating it from ground, means forming an excess potential drain for said conductor, said means comprising an insulating body suspended from said first named means, said body having an insulating strength less than said line conductor insulating means, an arcing pole at each end of said body, one pole conductively connected with the line conductor and means normally establishing a ground connection from said other pole, said means being adapted to interrupt said connection upon discharge therethrough and to reestablish said connection thereafter.
9. In a transmission line, a line conductor, means supporting said conductor and insulating it from ground, means forming an excess potential drain for said conductor, said means comprising an insulating body suspended from said first named means, said body having an insulating strength less than said line conductor insulating means, an arcing pole at each end of said body, the upper pole being conductively connected to the line, a tank suspended from said insulating body and in conductive connection with the lower pole, a second tank there below and connected to ground, a yieldable insulating tube between said tanks and extending into the lower tank, and a body of electrolyte in said tanks and tubes.
10. In a transmission system, a line conductor, means supporting said conductor and insulating it from ground, and an excess potential drain, said drain comprising an interrupter connected conductively to the line conductor, and a means forming an arc gap with one terminal connected to ground and the other terminal connected to the ground side of said interrupter.

In testimony whereof I have signed my name to this specification.

CHARLES E. BENNETT.
